United States Patent Office.

AUGUSTUS CONRADT, OF PHILADELPHIA, PENNSYLVANIA.

Design No. 3,085, dated June 30, 1868.

DESIGN FOR A FORK OR SPOON-HANDLE.

The Schedule referred to in these Letters Patent and making part of the same.

TO ALL WHOM IT MAY CONCERN:

Be it known that I, AUGUSTUS CONRADT, of the city of Philadelphia, in the State of Pennsylvania, have invented a new Design for a Handle for Spoons, Knives, Forks, &c., and other articles of table use, which, to the best of my knowledge and belief, has not been known or used previous to my application for a patent.

I do hereby declare that the following is an exact and correct description of the same, reference being had to the annexed drawing, and to letters of reference marked thereon.

The nature of my invention is a new design for a shank for a handle for spoons, &c., and other articles of table use, the shank being the centre part of the handle from letters A and B. This shank is tapering from the centre, C, to letter A, and tapering from the centre, C, to letter B, as shown in the drawing.

Having thus fully described the nature of my invention, I pray that the Commissioner of Patents may grant me Letters Patent for the design, as and for the purpose set forth and described.

What I claim as my invention, and desire to secure by Letters Patent, is—

The design for an ornamented shank for spoons, &c., tapering as described and shown.

Witnesses:

JAMES WILSON,
W. ADAMS.

AUGUSTUS CONRADT.
